[57] CLAIM

The ornamental design for a crayon, as shown and
described.

DESCRIPTION

FIG. 1 is a top perspective view of a crayon showing
my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

The shading employed in the drawings is for the pur-
pose of indicating color contrast.
